UNITED STATES PATENT OFFICE

2,040,216

AUTOMATIC CAMERA

Floyd A. Sears, Rome, N. Y.

Application June 8, 1934, Serial No. 729,675

3 Claims. (Cl. 95—53)

This invention relates to new and useful improvements in photography, and more particularly to an automatic camera for taking pictures at night.

- 5 An important object of the invention is to provide shutter operating means whereby a wild animal, reptile or bird can automatically photograph itself in a substantially fool-proof manner.
- 10 Other important objects and advantages of the invention will become apparent to the reader of the following specification.

In the drawing:

Figure 1 represents a top plan view of the camera and associated mechanism.

Figure 2 represents a vertical sectional view through the stop means.

Figure 3 represents a rear elevational view of the washer proper removed from its back, showing the balance wheel with which the pin engages to stop the mechanism thereof.

Figure 4 represents a perspective view of the stop pin.

Referring to the drawing wherein like numerals 25 designate like parts, it can be seen in Figure 1 that numeral 5 represents a platform having the camera, generally referred to by numeral 7, mounted thereon. The camera 7 is provided with the usual shutter 9 having the actuating arm 10.

30 In carrying out the present invention, a movable assembly is employed and consists of a plate 11 having the magnet 12 mounted thereon. The magnet 12 is provided with the U-shaped frame 13 between the free ends of which is swingably mounted the armature 14, this armature being provided with a contact extension 15. A post 17 on the plate 11 has a set screw 18 feedable therethrough and toward the armature 14 to limit the free movement thereof. A bifurcated

40 stem 19 is secured to the armature 14, while a socket member 20 having a reduced end is pivotally connected to the bifurcated portion of the stem 19. The socket end of this member 20 has a set screw 22 whereby one end of the strand 23 45 is secured in the socket. The other end of the strand connects to the lever 10 of the shutter 9. Spring contact fingers 30—31 form a switch in a circuit controlling the flash bulb 32. (See Figure 16.) The spring fingers 30—31 have insulation between the same, the fingers and block being secured to the upright 34 on the plate 11, this plate 11 being slidable on the guides 35—35 located on the aforementioned platform 5.

45 In addition to the magnet 12 and the switch, 50 generally referred to by numeral 38 and before

described, there is the stop watch which consists of the mechanism part 39 and the back plate 40. The back plate 40 is secured to the front side of the panel 41 and has an opening 42 therein through which the pin 43 protrudes. The panel 5 41 has a recess therein containing a spring 44 which acts against the head 45 of the pin to maintain the same urged against the lug 46 which depends from the armature 47 of the magnet 48, the latter being secured on a bracket 49 to the 10 rear side of the aforementioned panel 41. An arm 50 on the back side of the panel 41 supports a set screw 51 which acts to limit the movement of the armature 47. Numeral 52 represents a latch or detent for catching and holding 15 the armature when it is attracted to the magnet 48. At this point, it may be well to mention that the purpose of the stop watch is to cause the watch to stop at the moment the exposure is made so that the photographer can ascertain the exact 20 time the exposure is made and treat the film accordingly. That is, if the exposure is made late in the morning and there is some sunlight, then, of course, the photographer will be required to change his formula from that he would use if 25 the exposure had been made with only the aid of the flash bulb 32.

What is claimed is:—

1. In combination, a camera having a shutter, a magnet having an armature, a connection between the armature and the shutter, a stop watch adapted to be stopped at the moment the shutter is operated, said watch including a magnetically operated pin adapted to be driven into the operating mechanism of the watch when the shutter 30 magnet is operated.

2. In combination, a camera having a shutter, a magnet having an armature, a connection between the armature and the shutter, a stop watch 40 adapted to be stopped at the moment the shutter is operated, said watch including a magnetically operated pin adapted to be driven into the operating mechanism of the watch when the shutter magnet is operated, a platform for the camera, and a slidable plate on the platform upon which 45 the shutter magnet is mounted.

3. In combination, a camera having a shutter, a magnet having an armature, said armature having a socket member pivotally connected thereto, a set screw feedable into the socket, an 50 elongated flexible member having one end connected to the shutter and the other end disposed into the said socket member and secured thereto by said set screw.
